UNITED STATES PATENT OFFICE.

ALPHEUS W. ALTORFER, OF PEORIA, ILLINOIS.

DESIGN FOR A WASHING-MACHINE CABINET.

60,393.

Specification for Design.

Patented Feb. 14, 1922.

Application filed October 31, 1921. Serial No. 511,931. Term of patent 14 years.

To all whom it may concern:

Be it known that I, ALPHEUS W. ALTORFER, a citizen of the United States, residing at Peoria, in the county of Peoria and State of Illinois, have invented a new, original, and ornamental Design for Washing-Machine Cabinets, of which the following is a specification, reference being had to the accompanying drawings, forming part thereof.

Figure 1 is a perspective view looking at the front of the washing machine cabinet, showing my new design, and

Figure 2 is a perspective view looking at the rear of my washing machine cabinet.

I claim:—

The ornamental design for a washing machine cabinet, as shown.

ALPHEUS W. ALTORFER.
